UNITED STATES PATENT OFFICE.

METHODIE JWANOWITSCH KUSNEZOW, OF CHARKOW, RUSSIA, ASSIGNEE, BY MESNE ASSIGNMENTS, TO FERTH AMBOY CHEMICAL WORKS, A CORPORATION OF NEW JERSEY.

PROCESS FOR THE MANUFACTURE OF FORMALDEHYDE.

1,067,665.

Specification of Letters Patent.

Patented July 15, 1913.

No Drawing.

Application filed September 20, 1909. Serial No. 518,612.

To all whom it may concern:

Be it known that I, METHODIE JWANOWITSCH KUSNEZOW, chemist, a subject of the Emperor of Russia, residing at Charkow, Russia, have invented a certain new and useful Process for the Manufacture of Formaldehyde, of which the following is a specification.

The usual process for producing formaldehyde consists in passing heated air through methyl alcohol and conducting the mixture of methyl alcohol vapors and air thus obtained over heated copper. Besides copper, platinum, pumice stone and other materials have been tried as catalyzers, but without success, on account of the inferior yield obtained with these substances. I have found that metallic silver is a more advantageous catalyzer than copper and the other materials hitherto used.

The catalytic material is preferably prepared from a sheet of fine-meshed silver-wire netting by coiling it up into rolls or by piling up a considerable number of layers of the same and compressing them, or by precipitating the silver from a solution of a silver salt, for instance, from an ammoniacal solution of silver nitrate and then applying it to a suitable non-catalytic base or support, such as asbestos-wool, woven asbestos-fabric or pumice-stone, which has been first relieved of organic substances by calcination. The catalytic material is introduced into the catalyzing apparatus of usual construction, after which the apparatus is strongly heated and the mixture of methyl-alcohol vapors and air is conducted over the catalytic material. As soon as the reaction has been started, the external heating of the catalyzer may be interrupted. The reaction mixture is now conducted continuously over the catalytic mass, care being taken, that the temperature of the apparatus will not drop too low (not below 250° C.) because otherwise the reaction would be interrupted unless heat be supplied from outside.

A small portion of the methyl alcohol passes undecomposed through the contact substance, but as the aqueous solution of formaldehyde formed in commerce always con-

tains methyl alcohol, the reaction mixture produced may be utilized immediately.

The yield is almost equal to the theoretical quantity, which is not possible in using copper as a catalyzer. If the latter is used, a tolerable good yield may be obtained only by conducting over the catalyzer also a large excess of methyl alcohol vapor, a portion of which remains undecomposed, but in that case the methyl alcohol must be separated from the reaction mixture by distillation, entailing expense and waste of formaldehyde and methyl alcohol. This is at present the general standard of the art of making formaldehyde by oxidizing methyl alcohol by means of a copper catalyzer. Both the expenses for labor, etc., and the loss of raw material sustained in the various manipulations present considerable difficulties and objections in commercial practice and render the control of the process very inconvenient, a tolerable yield only being obtained owing to over-oxidation, and hence, the general efficiency of the copper contact process must be called a moderate one. Contrary to these shortcomings experienced in the commercial practice of the old process, my invention affords facilities which cannot be realized by the old process, most painstaking experiments under the various conditions having amply demonstrated that the highest and always reliable yield in formaldehyde can only be attained by abandoning the present universally adopted copper catalyzer for the metallic silver catalyzer.

In my process, it is immaterial to the yield, whether one runs the process with only a slight excess of methyl alcohol, or whether one even operates with a gas mixture the constituents of which exist in practically theoretical proportions.

This fact is of vital importance to the industry of formaldehyde manufacture and represents a great advance, particularly in view of the above cited facts showing that the yield is almost theoretical and that the portion of methyl alcohol which escapes the reaction is so small as to render the reaction mixture immediately available for commercial purposes. The efficiency of my process of oxidizing methyl alcohol to formaldehyde

by applying silver as a catalyst is far superior to that of any other process known at the present time, as the process may be so well defined as to guarantee a very high and 5 uniform yield.

What I claim is:—

The process for the manufacture of formaldehyde, which consists in conducting a mixture of methyl-alcohol vapors and air

over heated metallic silver, substantially as 10 described.

In testimony whereof I have hereunto set my hand in presence of two subscribing witnesses.

METHODIE JWANOWITSCH KUSNEZOW.

Witnesses:

PAUL SOROLOFF,

PETER ARKHOROPP.
